DESIGN FOR A CHAIR

Irving Salomon, Chicago, Ill.

Application May 23, 1936, Serial No. 62,795

Term of patent 7 years

To all whom it may concern:

Be it known that I, Irving Salomon, a citizen of the United States of America and a resident of Chicago, in the county of Cook and State of Illinois, have invented a new, original, and ornamental Design for a Chair, of which the following is a specification, reference being had to the accompanying drawing, forming a part thereof, and in which:

Fig. 1 is a perspective view of a chair embodying my new design;

Fig. 2 is a top plan view of the same; and
Fig. 3 is a side elevational view thereof.

I claim:

The ornamental design for a chair as shown.

IRVING SALOMON.
